(57) **CLAIM**

The ornamental design for a beverage container, as shown
and described.

DESCRIPTION

FIG. 1 is a top perspective view of a beverage container
showing our new design.

FIG. 2 is a bottom perspective view thereof.

FIG. 3 is a left side elevational view thereof.

FIG. 4 is a rear elevational view thereof.

FIG. 5 is a right side elevational view thereof.

FIG. 6 is a front elevational view thereof.

FIG. 7 is a top plan view thereof.

FIG. 8 is a bottom plan view thereof.

FIG. 9 is a top perspective view of a second embodiment
thereof.

FIG. 10 is a bottom perspective view thereof.

FIG. 11 is a left side elevational view thereof.

FIG. 12 is a rear elevational view thereof.

FIG. 13 is a right side elevational view thereof.

FIG. 14 is a front elevational view thereof.

FIG. 15 is a top plan view thereof.

FIG. 16 is a bottom plan view thereof.

FIG. 17 is a top perspective view of a third embodiment
thereof.

FIG. 18 is a bottom perspective view thereof.

FIG. 19 is a left side elevational view thereof.

FIG. 20 is a rear elevational view thereof.

FIG. 21 is a right side elevational view thereof.

FIG. 22 is a front elevational view thereof.

FIG. 23 is a top plan view thereof.

FIG. 24 is a bottom plan view thereof.

FIG. 25 is a top perspective view of a fourth embodiment
thereof.

FIG. 26 is a bottom perspective view thereof.

FIG. 27 is a left side elevational view thereof.

FIG. 28 is a rear elevational view thereof.

FIG. 29 is a right side elevational view thereof.

FIG. 30 is a front elevational view thereof.

FIG. 31 is a top plan view thereof; and,

FIG. 32 is a bottom plan view thereof.

The short, bold broken lines shown in the middle portion of
the beverage container are representative of stitching. The
longer broken lines of the beverage container form no part
of the claimed design.

1 Claim, 28 Drawing Sheets
